UNITED STATES PATENT OFFICE

96,566

DESIGN FOR A TUMBLER OR SIMILAR ARTICLE

Charles A. Straus, Richmond, Va., assignor to
The Straus Company, Richmond, Va., a corporation of Virginia

Application June 3, 1935, Serial No. 57,124

Term of patent 14 years

To all whom it may concern:

Be it known that I, Charles A. Straus, a citizen of the United States, residing at Richmond, in the county of Henrico and State of Virginia, have invented a new, original, and ornamental Design for a Tumbler or Similar Article, of which the following is a specification, reference being had to the accompanying drawing, forming part thereof.

Figure 1 is a view in side elevation of a tumbler or similar article, showing my new design.

I claim:—

The ornamental design for a tumbler or similar article, as shown.

CHAS. A. STRAUS.
